AMMUNITION BOX

John F. Haberlin, Seattle, Wash., assignor to
 Boeing Airplane Company, a corporation of
 Delaware

Application December 4, 1944, Serial No. 566,570

11 Claims. (Cl. 89—34)

1

Reliably supplying ammunition to a machine gun mounted in a wing of a fighter or attack airplane presents a problem. The space in which the ammunition may be stored is limited, and both the gun and the ammunition boxes are inaccessible to the crew during flight of the airplane. Nevertheless, for a fighting airplane to be effective, positive feed of the ammunition to such a wing machine gun must be assured. At the same time an adequate supply of ammunition must be available for each gun.

Heretofore booster mechanism driven by an electric motor independently of the gun has been used to drag a long cartridge belt to a point adjacent to the gun, thus relieving the gun mechanism itself from the major portion of the ammunition belt drag. This expedient has made the use of larger ammunition boxes feasible. Nevertheless the practical size of such ammunition boxes is limited. The depth of such boxes is usually restricted by the thickness of the wing, which often is quite thin in airplanes of such type.

If the wing thickness is not a controlling factor, the height through which the booster must lift the ammunition belt must be taken into consideration in establishing the maximum depth of the storage box. Only one tier of ammunition is permissible ordinarily because the stored ammunition must usually be aligned with the breech of the machine gun. The only other dimension of the ammunition box which can be varied is its length. If this dimension is too great the ammunition will not be fed evenly, because the strain on the booster varies greatly as the belt is fed first from one end of the box and then from the other.

Moreover, when approximately half of the ammunition or more has been removed from a long box the rest of the ammunition may be thrown about in it as the airplane executes various maneuvers, which may place a sufficient load on the electric booster drive and the machine gun mechanism to prevent the ammunition being fed to the gun at a critical time. Partitions have been placed transversely of such a box to divide it into small compartments, but when that nearest the gun has been emptied a section of the belt from the next compartment frequently cascades into the former compartment, as the airplane executes a quick maneuver, thus burying a portion of the belt nearer the gun. The overrun belt portion thus places such a heavy load on the portion of the belt under it that the booster cannot withdraw such portion of the belt from beneath

2

the pile and feed it to the gun, causing the gun to fail.

I have devised an ammunition box which overcomes the disadvantages of previous installations, and yet such box may be of a capacity greatly exceeding that of the largest box which has been practical heretofore.

It is a principal object of my invention to provide a composite ammunition box of large capacity which is not any deeper than conventional boxes, the increase in capacity being obtained by extending the length of the box. Despite the larger capacity of such a box, it is an object to remove ammunition from its farther end without increasing the load on the booster drive appreciably, yet no additional auxiliary drive mechanism is required.

A further object is to control the ammunition in such a large, partitioned ammunition box in a manner to prevent violent maneuvers of the airplane throwing the ammunition about in the box excessively, but such control will not interfere with the ammunition being fed reliably and continuously to the gun as it is required. Despite the provision of partitions an appreciably greater load is not imposed upon the booster drive mechanism at any one time than at any other. In fact the load on the booster drive mechanism is very little greater when the ammunition box has been nearly emptied than when it is almost full.

A further advantage of my mechanism is the simplicity of its construction and the effectiveness with which it operates automatically in accomplishing the purposes mentioned above. It is also an object to enable such mechanism to be adjusted readily for application to ammunition boxes designed to store ammunition of different calibre.

For the purpose of describing my invention, I have illustrated in the drawings an ammunition container having three sections, but it will be appreciated that the same principles may be incorporated in a box having a greater number of sections.

Figure 1 is longitudinal sectional view through an ammunition box incorporating my invention.

Figure 2 is a fragmentary section through a portion of the ammunition box shown in Figure 1 taken on line 2—2 of that figure. Figure 3 is a cross-sectional view similar to Figure 2, but showing part of the mechanism altered to accommodate ammunition of larger calibre.

Figure 4 is a fragmentary longitudinal sectional view taken on line 4—4 of Figure 2. Figure

5 is a longitudinal sectional view through the ammunition box comparable to that of Figure 4, but taken through the central portion of Figure 1.

In the description of my invention I have used the term "ammunition box" or "ammunition container" to designate the composite structure shown in Figure 1, which includes several compartments 1, 10 and 11. These compartments may be formed merely by providing partitions within a unitary long casing. In order to enable the capacity of an installation to be varied or selected readily, however, I prefer that these compartments be separate units, as illustrated in the drawings.

However many compartment units are employed, the ammunition belt will be fed from the compartment 1 nearest to the gun by a booster drive sprocket 12 of customary type, rotated by an electric motor. It is not necessary that such a booster drive be provided in order to utilize my invention, but in most instances such a drive is desirable. The compartment unit 11 at the end of the ammunition box remote from compartment 1 may be of convenient construction and will not incorporate features of my invention described below which are included in the other compartment units.

The intermediate unit 10 includes special features of my invention, but does not have a booster drive such as provided in compartment 1. The number of intermediate units 10 inserted between the two end compartments 1 and 11 may be varied at will. Some installations may not include any of these intermediate units, and others may incorporate several, depending upon the total capacity of the container required.

The ammunition belt formed of shells S and conventional links L are laid back and forth in a continuous chain until the container has been filled completely. If the container is divided the most remote compartment 11 is filled in this manner first, and then the belt passes to the bottom of compartment 10 in which an additional section of the belt is laid back and forth until this compartment has been filled. From compartment 10 the belt passes to the bottom of compartment 1 which holds the final section in the same way.

To feed the ammunition belt from such a container to the machine gun, the booster sprocket first withdraws the section of the cartridge belt from compartment 1, next that from compartment 10, or from several such compartments in succession, and finally from compartment 11. This is clearly illustrated in Figure 1 of the drawing where the section has been completely removed from compartment 1, almost entirely removed from compartment 10, and none of the belt section in compartment 11 has been removed.

If an ammunition box is merely divided into compartments, or if several individual compartment units are arranged in the manner shown in Figure 1, without the provision of any special control mechanism like that to be described hereafter, the ammunition belt will droop into each empty compartment in the manner illustrated in compartment 10 of Figure 1. As the booster drive pulls the ammunition belt, therefore, it will surge, some or all of the drooping portions being drawn upward to a critical point, and then the tension thus created in the belt suddenly withdraws a considerable length from a compartment at the right, again increasing

5 the amount of droop in each compartment to the left and decreasing the tension.

During normal operation such an arrangement is undesirable because of the fluctuating load placed upon the booster drive mechanism. The principal disadvantage of such mechanism, however, is that various maneuvers of the airplane, coinciding with a period of increased tension in the ammunition belt, occasionally cause 10 a portion of the belt from a compartment farther from the gun to overrun the drooping portion of the belt in the adjacent compartment nearer the gun and pile on top of it. Such excess belt creates such a load on the underneath belt portion that it cannot be withdrawn from beneath the pile by the booster, and consequently the machine gun is put out of commission.

20 In order to secure the advantages of a compartment type of ammunition box without its disadvantages, I have provided a bridge 2 in each compartment which will remain in the pendent position shown in Figure 5 and in compartment 10 of Figure 1 as long as there is a section 25 of ammunition belt of any appreciable length in such compartment. When a belt portion begins to be drawn from a compartment at the right to the adjacent compartment on the left, however, the bridge 2 of the latter compartment will be swung upward automatically into the horizontal position shown in compartment 1 of Figure 1, and in Figure 4. In that position the bridge will effectively close its compartment to the ammunition belt and serve as a support and guide for the portions of the belt drawn from compartments at the right, thus preventing the ammunition belt drooping down into a compartment which has been emptied.

30 An important feature of my invention is the mechanism which I have devised for swinging the bridge 2 in each compartment upward automatically when such compartment has been substantially emptied of ammunition. Such mechanism is shown most clearly in Figures 4 and 5. The bridge 2 is pivoted upon a shaft 20, which 35 may be supported by a channel-shaped bracket 21 secured to the wall of the compartment having the opening 13 into which the cartridge belt may be fed from a compartment at the right.

40 As long as a given compartment contains a sufficient length of ammunition belt so that no appreciable tension is exerted on the belt portion passing from the next compartment through the feed aperture 13, the bridge 2 will remain in the pendent position shown in Figure 5, suspended by shaft 20. The ammunition belt section extending through feed aperture 13 passes over a sprocket 22 secured to shaft 20, to which is also secured a spur gear 23. When 45 the bridge 2 is in operative position, shown in Figure 5, this spur gear will be in mesh with an arcuate rack 24 formed on the end of an arm 25.

50 The last portion of the section of ammunition belt being withdrawn from a compartment forms a catenary curve, as appears in compartment 10 of Figure 1, and the weight of such curved portion will exert a tension upon the portion of the ammunition belt passing through feed aperture 13. This force will draw ammunition through the feed aperture from a compartment at the right. The portion of the ammunition belt thus moved is engaged with 55 sprocket 22, and consequently will rotate it in a counterclockwise direction as viewed in Figure 5. Gear 23, being rotated counterclockwise 60 correspondingly, will turn the arcuate rack 24

in a clockwise direction, so that arm 25 will progress bodily clockwise around shaft 22 to swing bridge 2 upward about such shaft into the horizontal position shown in Figure 4.

As the swinging end of bridge 2 approaches its upper position, it will engage a spring latch 15 secured on the wall of the compartment in which the discharge opening 14 is formed. The swinging end of bridge 2 presses this latch outward until it passes above the latch tip.

Simultaneously with the raising of bridge 2 into the horizontal position of Figure 4, pin 26, movable lengthwise of a slot in the under side of bridge 2, will be shifted somewhat to the right relative to the bridge, since such pin is carried by arm 25 which, during raising of the bridge, cannot move lengthwise but merely rotates. This arm has in it a keyhole slot 27 adjacent to rack 24, through which extends a flat bar 28 carried by bracket 21 and secured against rotation relative to it. Lateral movement of arm 25 along bar 28 is prevented by spacer tubes 28' encircling such bar and interposed between the opposite sides of bracket 21 and arm 25.

The width of bar 28 extends horizontally and its thickness is vertical. The circular portion of keyhole slot 27 is of a diameter substantially equal to the width of the bar, so that when the bar is engaged in this portion of the slot arm 25 may swing about such bar but cannot move lengthwise. When the bridge has been raised into horizontal position so that its free end clears latch 15, the parallel-sided portion of slot 27 has been brought into a position adjacent to the edge of the bar. The width of this slot portion is sufficiently great to receive the thickness of the bar, but in any other position the bar cannot enter this portion of the slot. When the bridge 2 reaches horizontal position, therefore, a spring 29, having its ends fixed to arm 25 and encircling a spacer tube 28', draws arm 25 to the right so that the narrow portion of the keyhole slot 27 fits over the bar.

Such lengthwise movement of arm 25 will completely disengage arcuate rack 24 from spur gear 23, so that such gear may turn freely with sprocket 22 as the ammunition is drawn across the bridge without operating the bridge-raising mechanism. Moreover when its slot is thus engaged with the bar, arm 25 is held against rotation and forms a brace tending to hold up the swinging end of the bridge at the left of Figure 4. The slot 27 and bar 28 should, however, be proportioned so that such bridge end will also rest on the spring latch 15.

In order to reset the bridge to the pendent position of Figure 5 when it is desired to fill the ammunition box again, latch 15 may be drawn outward and arm 25 shifted to the left, by reaching behind gear 23, to release the narrow portion of slot 27 from bar 28. As the bridge is lowered, rack 24 will mesh with gear 23 again so that the parts will assume the positions shown in Figure 5, ready for a further automatic bridge-raising movement.

As shown in Figures 2 and 3 the bridge 2 need not extend across the full width of the container as long as it supports an appreciable zone at the center of the ammunition belt. The two wheels of sprocket 22 are received in slots in the right end of bridge 2 when they are arranged as shown in Figure 2. If an ammunition belt incorporating ammunition of a larger calibre is to be handled, sprocket wheels having larger notches and arranged with their hubs in reversed position in

the manner shown in Figure 3 may be substituted for those of Figure 2. While their hubs are secured on the same portions of shaft 20, the disk portions are spaced apart a considerably greater distance. The arrangement of the sprocket parts shown in Figure 2 could be employed, for example, for a .50 calibre machine gun belt, whereas the arrangement of Figure 3 might be utilized with ammunition for a 20-mm. gun.

Whatever the size of ammunition being fed it will be evident that the same general type of construction may be employed in the ammunition box. The bridges of the various compartments will be raised successively in the manner described to form a straight path along which the ammunition is guided from the compartment from which it is removed to the booster drive. No appreciable stress is placed upon the booster drive by ammunition moving across such bridges, but almost the entire load is created by lifting the ammunition from the compartment from which it is being removed. It will be evident that the number of intermediate compartments 19 between the booster compartment 1 and the end compartment 11 at the right of Figure 1 may be increased or decreased within wide limits according to the amount of ammunition desired for a particular installation.

Although it is preferred that the ammunition box be divided into compartments, either by use of partitions or by assembling a plurality of box units, my bridging mechanism would be useful in a long ammunition box which had no partitions in that the bridges themselves, in pendent position, would constitute partitions between adjacent piles of ammunition belt. The belt would pass from the top of a pile at the right to the bottom of the adjacent pile at the left over a sprocket 22 as previously described. As ammunition from each pile begins to be fed toward the gun the bridge at the left of such pile would be raised automatically. Such arrangement, while possible, is not as desirable as a construction in which each pile is confined on all sides by a wall, because when a bridge is raised there is a possibility of a section of ammunition belt being flung from a partially depleted pile into the space beneath such raised bridge.

50 I claim as my invention:

1. An ammunition box comprising a container adapted to receive a section of ammunition belt folded back and forth to form a pile, said container having an outlet opening for ammunition belt 55 in one side thereof spaced sufficiently above the container's bottom for accommodation of such ammunition belt pile below it, and having an inlet opening for ammunition belt in the opposite side thereof also spaced sufficiently above the container's bottom for accommodation of such ammunition belt pile below it, supporting means operable to support above the bottom of said container a section of ammunition belt extending between such inlet opening and such outlet opening, means driven by movement of a portion of the ammunition belt when the major portion of such ammunition belt pile has been discharged through such outlet opening, and means operatively connecting said driven means and said supporting means and operable to effect positive movement of said supporting means by said driven means upon ammunition belt effected movement thereof, to position said supporting means between such outlet and inlet openings.

75 2. An ammunition box comprising a container

adapted to receive a section of ammunition belt folded back and forth to form a pile, said container having an outlet opening for ammunition belt in one side thereof spaced sufficiently above the container's bottom for accommodation of such ammunition belt pile below it, and having an inlet opening for ammunition belt in the opposite side thereof also spaced sufficiently above the container's bottom for accommodation of such ammunition belt pile below it, supporting means operable to support above the bottom of said container a section of ammunition belt in a position extending substantially linearly between such inlet opening and such outlet opening, and to guide such belt for direct movement between such openings, means driven by movement of a portion of the ammunition belt when the major portion of such ammunition belt pile has been discharged through such outlet opening, and means operatively connecting said driven means and said supporting means and operable to effect positive movement of said supporting means by said driven means upon ammunition belt effected movement thereof, to position said supporting means between such outlet and inlet openings.

3. An ammunition box comprising a container adapted to receive a section of ammunition belt folded back and forth to form a pile, said container having an outlet opening for ammunition belt in one side thereof spaced sufficiently above the container's bottom for accommodation of such ammunition belt pile below it, and having an inlet opening for ammunition belt in the opposite side thereof also spaced sufficiently above the container's bottom for accommodation of such ammunition belt pile below it, bridging means movable from an inoperative position into an operative position between such outlet and inlet openings for supporting a section of ammunition belt extending between such inlet opening and such outlet opening, means driven by ammunition belt moving into said container through such inlet opening when the major portion of such ammunition belt pile has been discharged through such outlet opening, and means operatively connecting said driven means and said supporting means and operable to effect positive movement of said supporting means by said driven means upon ammunition belt effected movement thereof, to move said bridging means from its inoperative position into its operative position.

4. An ammunition box comprising a container adapted to receive a section of ammunition belt folded back and forth to form a pile, said container having an outlet opening for ammunition belt in one side thereof spaced sufficiently above the container's bottom for accommodation of such ammunition belt pile below it, and having an inlet opening for ammunition belt in the opposite side thereof also spaced sufficiently above the container's bottom for accommodation of such ammunition belt pile below it, a bridge member, means normally suspending said bridge member in pendent attitude adjacent to such inlet opening, and means engageable with a section of ammunition belt extending through such inlet opening, operatively connected to said bridge, and operable by movement of such ammunition belt to swing said bridge upward into a position spanning the space between such inlet and outlet openings for supporting and guiding a section of ammunition belt extending between such openings.

5. An ammunition box comprising a container

adapted to receive a section of ammunition belt folded back and forth to form a pile, said container having an outlet opening for ammunition belt in one side thereof spaced sufficiently above the container's bottom for accommodation of such ammunition belt pile below it, and having an inlet opening for ammunition belt in the opposite side thereof also spaced sufficiently above the container's bottom for accommodation of such ammunition belt pile below it, a bridge member, pivot means normally suspending said bridge member in pendent attitude adjacent to such inlet opening, a sprocket adjacent to such inlet opening and engageable by a section of ammunition belt extending therethrough, and means interposed between said sprocket and said bridge member, operable by rotation of said sprocket effected by movement of the ammunition belt engaged therewith to swing said bridge member into operative position spanning the space between said inlet and outlet openings.

6. The ammunition box defined in claim 5, and latch means engageable by the swinging end of the bridge member in operative position to support such end of the bridge member.

7. An ammunition box comprising a container adapted to receive a section of ammunition belt folded back and forth to form a pile, said container having an outlet opening for ammunition belt in one side thereof spaced sufficiently above the container's bottom for accommodation of such ammunition belt pile below it, and having an inlet opening for ammunition belt in the opposite side thereof also spaced sufficiently above the container's bottom for accommodation of such ammunition belt pile below it, a bridge member, pivot means normally suspending said bridge member in pendent attitude adjacent to such inlet opening, a sprocket adjacent to such inlet opening engageable by a section of ammunition belt extending therethrough, drive means interposed between said sprocket and said bridge member, operable by rotation of said sprocket effected by movement of the ammunition belt engaged therewith to swing said bridge member into position spanning the space between said inlet and outlet openings, and means operable to render said drive means inoperative when the bridge member has been raised into operative position.

8. An ammunition box comprising a container adapted to receive a section of ammunition belt folded back and forth to form a pile, said container having an outlet opening for ammunition belt in one side thereof spaced sufficiently above the container's bottom for accommodation of such ammunition belt pile below it, and having an inlet opening for ammunition belt in the opposite side thereof also spaced sufficiently above the container's bottom for accommodation of such ammunition belt pile below it, a bridge member, pivot means normally suspending said bridge member in pendent attitude adjacent to such inlet opening, an arm beneath said bridge member, a pivot disposed generally below said pivot means and supporting said arm, means slidably interconnecting the swinging end of said arm with the swinging end of said bridge member, a sprocket adjacent to such inlet opening and engageable by a section of ammunition belt extending therethrough, and gear means interposed between said sprocket and the pivoted end of said arm, operable by rotation of said sprocket effected by movement of the ammunition belt engaged therewith to swing said arm upward, thus to move said bridge member into operative posi-

tion spanning the space between said inlet and outlet openings.

9. The ammunition box defined in claim 8, and means operable to shift the arm lengthwise when the bridge member has been raised into operative position for disengaging the gear means to interrupt the drive between the sprocket and the arm.

10. An ammunition box comprising a container adapted to receive a section of ammunition belt folded back and forth to form a pile, said container having an outlet opening for ammunition belt in one side thereof spaced sufficiently above the container's bottom for accommodation of such ammunition belt pile below it, and having an inlet opening for ammunition belt in the opposite side thereof also spaced sufficiently above the container's bottom for accommodation of such ammunition belt pile below it, a bridge member, pivot means normally suspending said bridge member in pendent attitude adjacent to such inlet opening, a flat bar disposed generally below said pivot means and extending transversely of said bridge member, an arm beneath said bridge member having a keyhole slot in one end thereof through which said bar extends, such slot having a circular portion of a diameter substantially equal to the larger dimension of said bar, and a parallel sided portion of a width substantially equal to the thickness of said bar, means slidably interconnecting the swinging end of said arm with the swinging end of said bridge member, a sprocket adjacent to such inlet opening engageable by a section of ammunition belt extending therethrough, gear means interposed between said sprocket and the pivoted end of said arm operable by rotation of said sprocket effected by movement of the ammunition belt engaged therewith to swing said arm upward, thus to move said

bridge member into position spanning the space between said inlet and outlet openings, and means operable to shift said arm lengthwise when the bridge member has been raised into operative position, for disengaging said gear means to interrupt the drive between said sprocket and said arm and for engaging the parallel sided portion of the slot in said arm with said bar, to hold said arm against swinging movement, bracing said bridge member thereby.

11. An ammunition box comprising a container adapted to receive a section of ammunition belt folded back and forth to form a pile, said container having an outlet opening for ammunition belt in one side thereof spaced sufficiently above the container's bottom for accommodation of such ammunition belt pile below it, and having an inlet opening for ammunition belt in the opposite side thereof also spaced sufficiently above the container's bottom for accommodation of such ammunition belt pile below it, a bridge member, means normally suspending said bridge member in pendent attitude adjacent to one of such openings, and means operable to swing said bridge upward into a position spanning the space between such inlet and outlet openings for supporting and guiding a section of ammunition belt extending between such openings.
